UNITED STATES PATENT OFFICE.

FELIX L. ARNALL, OF GRANBY, MISSOURI.

SAFETY SWITCH.

Application filed October 7, 1925. Serial No. 61,058.

This invention relates to improvements in switches for railways, the general object of the invention being to provide the switch with locking means which will hold the 5 switch in set position even though the operating means have been damaged.

Another object of the invention is to so arrange the locking means that they can be locked in operative position by a suitable 10 lock so that they cannot be tampered with by an unauthorized person.

A further object of the invention is to provide means for automatically causing the locking device to lock the switch against 15 movement when the switch is moved back, to its normal position.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a transverse sectional view 30 through the switch part of a track showing the invention in use, with the parts thereof in position to permit the switch to be operated.

Figure 2 is a similar view but showing the 35 device in position for locking the switch against movement.

Figure 3 is a plan view of Figure 2.

Figure 4 is a view of one of the locking 40 members.

Figure 5 is a view of the pawl.

Figure 6 is a view similar to Figure 2, but showing the parts in a position where the dog 15 engages the top of the dog 11.

In these views, A indicates the rails of the 45 main line, B the rails of the branch line and C the switch points. These points are connected together by the bar 1 which is fastened by a link 2 to an arm 3 of the switch operating shaft 4, rotatably mounted in the stand 5 and having the handle 6 attached thereto so that it can be rotated to move the switch points to cause the train to continue over the main line or to take the branch line. These parts are of the well known or any 50 desired construction and form no part of my invention.

In carrying out my invention, I provide a rod 7 which is slidably mounted in the uprights 8 arranged in a casing 9, located under a portion of the track. One end of this 60 rod is extended upwardly and passes through a hole 10 in the top of the casing and is connected to one of the switch points C. The other end of the rod abuts against the pivot 65 ed dog 11 in the casing 9 which is normally held in its forward position by a spring 12. A spring 13 may be used to hold the rod 7 in its forward position, if desired, or necessary. This spring is placed between the uprights 8 and abuts a collar 14 fastened to 70 the rod. The dog 11 has a notch 11' therein and a locking dog 15, also pivoted in the casing, is adapted to engage said notch, when the dog 15 is swung forwardly, to prevent movement of the dog 11 and thereby the 75 switch points and the rod 7. A rod 16 is slidably arranged in the casing 9 and passes through one end of the casing and into a casing 17. One end of this rod is pivoted to the locking dog 15 and its other end is connected by a link 18 to the depending part or 80 arm 19 of a shaft 20 which is journaled in brackets connected with some of the ties of the track. A handle 21 is connected with the shaft so that it can be rocked and this handle, 85 when in its lowest position, will engage a bracket 22 which is provided with holes 23 so that a padlock or the like can be passed through the bracket to lock the handle therein. In this position of the parts, the rod 16 90 will have moved the dog 15 over against the dog 11 and thus prevent rearward movement of said dog 11 so that the switch points are held against movement. Before the switch can be thrown, the handle 21 must be lifted, 95 as shown in Figure 1, and the resultant rocking of the shaft will cause link 18 to push the rod 16 rearwardly and thus move the dog 15 away from the dog 11. Then the switch 100 can be thrown in the usual manner as the rod 7 will push the dog 11 to the right in Figure 1, as the movement of this dog will not be interfered with by the dog 15. A spring 24 tends to move the parts to locking 105 position by engaging a collar 25 on the rod 16 and a portion of the casing 9. A pawl 26 is pivoted in the casing 17 and is adapted to engage a notch 27 in the rod 16 to prevent the spring 24 from moving the rod 16 in a reverse direction from which it has been 110 moved by the raising of the handle 21. A link 28 is pivoted to the rod 7 and has a

slot 29 at its other end for engaging a projection 30 on the lower end of the pawl, so that when the rod 7 is moved to the right in Figure 1, by the movement of the switch, the link 28 will swing the pawl 18 out of the notch 27 and thus permit the spring 24 to move the parts to locking position. However, this action is delayed, owing to the slot and pin connection between the link and pawl, until the dog 11 has been moved far enough to prevent the dog 15 from entering the notch 11' in the dog 11. Thus the dog 15 will engage the rounded upper end of the dog 11 but will not prevent movement of said dog 11 as shown in Figure 6. Then when the switch points are moved back to their normal position, the dog 11 will return to its upright position under the action of the spring 12 and the dog 15 will drop into the notch 11' and thus again lock the parts in this position, and the switch cannot be again moved until the handle 21 is lifted. Holes 31 are arranged in the casings to prevent water from collecting therein.

With this device, the switch is locked in position and cannot be moved until the lever 21 is unlocked and raised. Then when the switch is moved to permit a train to pass from the main line to the branch line and then moved back to its normal position, the locking device will automatically again lock the switch against movement. The device will hold the switch against movement even though the switch stand has been knocked down or injured.

It is thought from the foregoing description that the advantages and novel features of my invention will be readily apparent.

I desire it to be understood that I may

make changes in the construction and in the combination and arrangement of the several parts, provided that such changes fall within the scope of the appended claims.

What I claim is:—

1. A locking device for a railroad switch, comprising a member, means for moving the member by the switch, a locking dog for preventing movement of said member, spring means for moving the dog to locking position, manually operated means associated with the spring means for moving the dog to unlocking position, a pawl for holding the parts in locking position and a connection between the movable means for the member and the pawl for releasing the pawl after the switch has been moved to enable the parts to return to locking position.

2. A locking device for a railroad switch, comprising a casing arranged under the track adjacent the switch, a notched dog in the casing, a locking dog in the casing for engaging the notch to hold the first dog against movement, a rod connected with a switch point and slidably arranged in the casing and arranged to move the notched dog when the switch is moved, a spring pressed rod pivoted to the second dog, a hand operated part connected with the rod for moving the same to move the dog to unlocking position, a pawl for holding the spring pressed rod with the dog in unlocking position and a link connecting the pawl with the rod attached to the switch point for moving the pawl to inactive position when the switch is moved.

In testimony whereof I affix my signature.
FELIX L. ARNALL.
